UNITED STATES PATENT OFFICE.

WALTER FRANCIS SOLLIS AND JAMES LAMBERT, OF BATTERSEA, LONDON, ENGLAND.

APPARATUS FOR CASTING METALS.

1,150,974.

Specification of Letters Patent. Patented Aug. 24, 1915.

Application filed March 23, 1915. Serial No. 16,525.

To all whom it may concern:

Be it known that we, WALTER FRANCIS SOLLIS and JAMES LAMBERT, both subjects of the King of Great Britain, residing at 5 157 Ingrave street, Battersea, London, S. W., England, and 69 Weybridge street, Battersea, London, S. W., England, respectively, have invented certain new and useful Improvements in Apparatus for Casting Metals, of which the following is a specification.

This invention relates to the method of casting metals wherein pressure is exerted upon the metal by centrifugal force as it 15 enters the mold, with the object of preventing "short pours" and blowholes, and with a view to obtaining a solid and homogeneous metallic body that is a true replica in every respect of the mold. In processes of 20 a like type heretofore contemplated it has been necessary to have special molding boxes or flasks for each article molded or to arrange the molds symmetrically upon the rotary table in a manner that required 25 a common central pouring hole, or runner adapted to receive the metal from the ladle, and in which the risers had a common overflow.

This invention does not contemplate special molds or molding boxes but apparatus whereby ordinary molding boxes may be employed and yet receive the metal under the influence of centrifugal pressure.

In carrying this invention into effect a 35 turntable is provided and driven by suitable means, the said turntable being so slotted over its face that the pouring hole of the box containing the mold to be cast can be centralized with respect to the turntable center of rotation. In cases however where two or several molds require to be cast from a pour in succession then a bent funnel is employed whose end remote from the mouth 40 may be inserted into the runner of each mold in turn while the mouth of the funnel is centralized to receive the molten liquid metal; the runner centers of each box being of equal radii from the turntable center.

In order however to more fully describe 50 this invention reference is made to the accompanying drawings in which:—

Figure 1. shows in vertical part sectional elevation the apparatus for and method of operating the invention. Fig. 2. shows detail of portable pouring funnel shown in operative relation with respect to the run-

ner of a mold upon a table as in Fig. 1. Fig. 3, shows an apparatus for accommodating more than one flask.

In the drawings, a rotary table 1 is 60 mounted on a shaft 2, driven by belt 3 or equivalent convenient means, the said shaft being journaled in a footstep bearing 4. The table 1 is as shown conveniently and specially slotted chuck plate fashion as at 65 5 to accommodate holding down bolts 6, which bolts secure the ordinary molds or flasks 7 adjustably upon said table. The said flask 7 in the example shown is disposed so as to have its runner 8 centrally disposed with regard to the axis of rotation of the table, a plumb-bob 9 being suitably placed to insure this. In operation in this form of the invention metal is poured into the runner in the well known way while 75 the table is revolving. Immediately the metal reaches the mold it feels the effect of centrifugal force, which force increases as the metal gets farther from the axis, the effect being to drive the metal into the 80 mold and accurately fill the same, the metal mounting to the riser 10 where its further progress may be prevented by cessation of rotation.

In Fig. 3 is shown a method of placing 85 several ordinary molding boxes upon the table 1. In this case they are arranged radially as near as possible to the center, but with the pouring holes all practically equidistant from the axis. In this case a runner mouth 18 is provided, see Fig. 2, which can be placed in any one of the runners, so that the mouth of this device becomes central with the axis of the table. This runner mouth 18 may be detached from any one 90 of the molds and used successively for the other molds on the table.

In practice, the speed at which the table is revolved is determined by the type of metal to be cast, and the size and weight of the castings. For example ordinary castings in cast iron, running from 1 to 15 lbs. in weight may be poured in with the table revolving at 40 revolutions per minute, the end of the mold in the flasks having a radial length from the center of not more than one foot, or 15 inches at the most. For lighter metals such as aluminium and its alloys, the speed may either be increased or the flasks placed farther from the center.

It will be seen that in operation exactly 110 the conditions required for obtaining good

castings are by these simple means accomplished, and by having the funnel device and rotary turntable no other devices than those found in any ordinary foundry are necessary.

The operator can if so desired, vary the speed of the rotating table during the process of casting, this being desirable in some types of castings so as to regulate the force 10 which causes the metal to enter the mold, with a view to consolidating the casting after its farther confines have set or become plastic, this can be done after the pouring device has been removed.

15 We claim:—

1. In an apparatus for producing metal castings, a rotatable turn table the face of which is provided with slots so arranged that a molding flask of ordinary pattern 20 may be secured upon its face either so that the pouring hole may coincide with the axis of revolution or so that it may be held at a distance therefrom.

2. In an apparatus for producing metal 25 castings in combination, a rotatable turn table the face of which is provided with a plurality of slots so arranged that a molding flask of ordinary pattern may be secured on

its face either so that the pouring hole may coincide with the axis of revolution or so 30 that it may be held at a distance therefrom, a plurality of molding flasks of ordinary pattern secured to said table in such a manner that their pouring holes are removed from the axis of rotation, and a pouring 35 funnel adapted to enter the pouring hole of each of the said flasks successively and to deliver metal thereinto while the table is being rotated.

3. A pouring mouth for molds comprising an enlarged mouth portion and a delivery portion arranged substantially parallel, the mouth portion opening in one direction and the delivery portion opening in the opposite direction, an intermediate portion connecting said portions, and a flange surrounding said delivery portion, substantially at right angles thereto.

In testimony whereof we affix our signatures in presence of two witnesses.

WALTER FRANCIS SOLLIS.
JAMES LAMBERT.
